UNITED STATES PATENT OFFICE.

OTTO H. L. WERNICKE, OF GRAND RAPIDS, MICHIGAN, ASSIGNOR OF ONE-HALF TO
MOSES HENRY LANE, OF KALAMAZOO, MICHIGAN.

CULVERT.

Application filed September 21, 1920. Serial No. 411,738.

To all whom it may concern:

Be it known that I, OTTO H. L. WERNICKE, citizen of the United States, residing at Grand Rapids, county of Kent, State 5 of Michigan, have invented certain new and useful Improvements in Culverts, of which the following is a specification.

This invention relates to improvements in culverts.

10 The main objects of this invention are,

First, to provide an improved culvert which may be formed in sections and the sections readily assembled or held on a suitable foundation at the place of installation;

15 Second, to provide an improved culvert section which may be conveniently handled and transported with little danger of being broken.

20 Further objects, and objects relating to structural details, will definitely appear from the detailed description to follow.

I accomplish the objects of my invention by the devices and means described in the following specification. The invention is 25 clearly defined and pointed out in the claims.

A structure which is a preferred embodiment of my invention is clearly illustrated in the accompanying drawing forming a part of this specification, in which:

30 Fig. I is an end view of one of my improved culvert sections.

Fig. II is a transverse section through a culvert embodying the features of my invention on line 2—2 of Fig. IV.

35 Fig. III is a similar transverse section illustrating the method of installation.

Fig. IV is a detail longitudinal section on a line corresponding to line 4—4 of Fig. II.

40 Fig. V is a detail section of a modified form of my invention.

In the drawing similar reference characters refer to similar parts throughout the several views, and the sectional views are taken looking in the direction of the little 45 arrows at the ends of the section lines.

Referring to the drawing I provide a plurality of culvert sections designated generally by the numeral 1 and each comprising a top portion 2, side portions 3 and bottom portions 4 formed integrally of concrete, the bottom portions being in the form of inwardly projecting flanges on the lower edges of the side portions 3. In the preferred embodiment of my invention the bottom portions are connected by the trans-

verse reinforcing bars 5 which are embedded therein and extend between them. The edges 6 of the bottom portions are preferably upwardly beveled as shown.

The sections are laid end to end or abutting, the meeting ends in the embodiment illustrated being provided with coacting external and internal shoulders 7 and 8 respectively, forming interlapping joints.

Concrete stringer or tie piece 9 is preferably continuous as shown in the drawing and is laid at the place of installation. This stringer or tie piece fills in between the edges of the bottom portions 4 and preferably extends below the same as shown in the drawing. It is not generally necessary that the stringer extend to the outer edges of the sections, as the portions 10 thereof may be effectively supported by the earth in most situations or in most conditions to be found in installing the same. The stringer fills in between the bottom portions and embeds the transverse members 5 as is clearly shown providing a continuous support for and a tie between the sections. Longitudinal reinforcing or tie members 11 are preferably provided in the stringer member.

The head walls 12 are preferably supplied in standardized units, but may be built on the ground to meet the requirements of the particular installation, the same being formed by means of forms and preferably filled so as to form an integral part with the stringer member. In the modification shown in Fig. V the transverse bars 5' do not extend from side to side.

The culvert sections may be built at a factory and transported to the place of installation, while the stringer member is, as stated, built on the ground.

45 Culverts embodying the features of my invention are very economically produced and installed. The culvert sections are so supported and tied together by the stringer member that they are firmly retained in position and are not likely to get out of operative relation as a result of settling of the ground or the like.

I have illustrated and described my improvement in embodiments which I consider very practical. I have not attempted to illustrate or describe certain modifications or adaptations which may be found desirable to meet particular installations, as I believe the disclosures made will enable

those skilled in the art to which my invention relates to embody or adapt the same as may be desired.

Having thus described my invention, what I claim as new and desire to secure by Letters Patent is:

1. In a structure of the class described, the combination of abutting sections, each comprising integral top, sides and bottom portions, the edges of the bottom portions being substantially spaced and upwardly inclined, there being transverse reinforcing members embedded in and extending between said bottom portions, such reinforcing members being above the plane of the bottoms of said bottom portions, and a continuous concrete stringer extending below and filling between said bottom portions and embedding said reinforcing members.
2. In a structure of the class described, the combination of abutting sections, each comprising integral top, sides and bottom portions, the edges of the bottom portions

being substantially spaced and provided with opposed inclined edges and a continuous concrete stringer member extending below and filling between said bottom portions.

3. In a structure of the class described, the combination of abutting sections each comprising integral top and sides, each side having an integral inwardly projecting bottom portion, the edges of said portions being spaced, there being cross reinforcing members for said bottom portions disposed above the plane of the bottom of said bottom portions, and a stringer member extending beneath and filling between said bottom portions and embedding the said reinforcing members.

In witness whereof, I have hereunto set my hand and seal in the presence of two witnesses.

OTTO H. L. WERNICKE. [L. S.]
